UNITED STATES PATENT OFFICE.

WILLIAM F. VALCKE, JR., OF CHICAGO, ILLINOIS.

RHEOSTAT.

1,252,203.

Specification of Letters Patent. Patented Jan. 1, 1918.

Application filed October 30, 1916. Serial No. 128,582.

To all whom it may concern:

Be it known that I, WILLIAM F. VALCKE, Jr., a citizen of the United States, residing at Chicago, in the county of Cook, State of Illinois, have invented certain new and useful Improvements in Rheostats; and I do hereby declare the following to be a full, clear, and exact description of the invention, such as will enable others skilled in the art 10 to which it appertains to make and use the same.

This invention relates to electric light sockets, and has particular reference to a socket for regulating the amount of current 15 which is supplied to a lamp or other apparatus connected to the socket.

The object of the invention is to combine in a lamp socket adapted to be used in ordinary house wirings, a rheostatic element by 20 whose adjustment the amount of current which leaves the socket may be regulated to vary the degree of light in a lamp contained in the socket, or else to adjust the current for operating toys, and household appliances, 25 such as flat irons, heating bodies, percolators, fans or washing machines.

In carrying out the invention, it is also an object to construct a socket of the character above defined whose construction is not 30 complicated or expensive in manufacture, the ordinary socket structure being modified merely to the extent of providing new porcelains of such shape that they will contain the rheostatic element and the switch arm.

With the above objects in view and such other objects as may hereinafter appear, my invention will now be fully set forth and described, reference being had to the accompanying drawings.

40 In the drawings:—

Figure 1 is a side elevation of the lamp socket partly broken away in order to disclose the interior structure,

Fig. 2 is a section on line 2—2 of Fig. 1,

45 Fig. 3 is a rear elevation,

Fig. 4 is a section on line 4—4 of Fig. 1, and Fig. 5 is a diagrammatic view showing the wiring of the socket.

Referring more particularly to the drawings, 1 denotes the usual socket casing having the lead-in collar 2 for receiving the two-wire cable 3. Contained within the casing 1 is an upper porcelain 4 secured to the casing by means of screws 5 and a lower porce-

lain 6 which is secured to the porcelain 4 in 55 spaced relation by means of the bracket piece 7. The lower porcelain carries the usual threaded collar 8 and also secured thereto is the spring contact arm 9, the latter extending to the center of the porcelain to be 60 contacted by the central contact of the lamp.

The lower porcelain 6 is provided with an annular shoulder 10 which forms a seat for a coiled rheostatic element 11, the latter consisting of a continuous length of suitable 65 resistance wire, and being of sufficient length to overlie the greater part of the circumference of the annular shoulder 10, this being necessary in order to give the necessary wide range of current regulation necessary in satisfying the current requirements of various 70 electrical appliances. Rising centrally from the raised portion of the porcelain 6 is a spindle 12 upon which is pivotally mounted the swinging arm 13, the latter being constructed of any suitable conductive metal, and extending through a slot 14 formed in the side of the casing 1, so as to be accessible for manual manipulation. Extending downwardly from the swinging arm 13 into contact with the coil 11 is a brush 15 which completes the circuit through the swinging arm 13 when the coil in the device is wired. The slot 14 is of sufficient extent to permit 75 the arm 13 to swing substantially over the 80 entire length of the coil 11, so that the widest range of current regulation may be had.

After the cable 3 has been split into its component wires within the dome of the casing 1, one of the wires 16 is extended 90 through the groove 17 in the side of the porcelain 4, and is secured to a contact plate 18 which is suitably brazed or otherwise secured to the threaded shell 8, thus one wire is directly connected to the socket proper. 95 The other wire 19 is carried through a groove 20 diametrically opposite the groove 17, and passing below the plate is connected by means of the screw 21 to the swinging arm 13. One of the ends of the coil 11 is 100 connected by means of a wire 22, or other connecting element with the spring contact 9. Then when a lamp or connecting plug is inserted into the shell 8 so as to close the circuit across the contacts 18 and 9 the current which is fed thereto may be regulated 105 within a wide range by operating the switch arm 13 over the coil 11, the current passing

to the appliance depending upon the position of the arm 13 in its contact with the coil 11.

What I claim as my invention is:—

- 5 1. In a lamp socket, the combination of a porcelain having an annular shoulder formed at its upper end, a resistance coil wound around said shoulder, a swinging arm centrally mounted upon the porcelain and 10 having a brush wiping on said coil, plug contacts associated with the socket, one of said contacts being connected to one end of said coil, and means for connecting electric wires to the opposite contact and to said 15 swinging arm.
- 2. In a lamp socket, the combination of a porcelain having an annular shoulder

formed at its upper end, a resistance coil seated on said shoulder and having its turns exposed in a substantially semi-circular contact strip, a swinging arm mounted on said porcelain and having a brush movably bearing on said strip, plug contacts associated with the socket, one of said contacts being connected to one end of said coil, and means 20 for connecting electric wires to the opposite contact and to said arm.

In testimony whereof, I affix my signature, in the presence of two witnesses.

WILLIAM F. VALCKE, JR.
